ATTORNEY

UNITED STATES PATENT OFFICE.

WILL DEAN BURNON, OF SPENCER, NORTH CAROLINA, ASSIGNOR OF ONE-HALF TO
RICHARD P. CARTER, OF SPENCER, NORTH CAROLINA.

CAR-REGISTERING DEVICE.

Application filed August 23, 1921. Serial No. 494,686.

To all whom it may concern:

Be it known that I, WILL D. BURNON, a citizen of the United States, residing at Spencer, in the county of Rowan and State of North Carolina, have invented new and useful Improvements in Car-Registering Devices, of which the following is a specification.

This invention relates to a registering and recording device, the general object of the invention being to make a record of persons entering and leaving a place or building so that it will be a simple matter to tell at any time the number of persons entering and leaving.

While the invention is mainly designed for cars, such as street cars and railroad cars it can be used for keeping records of persons entering and leaving moving picture places, baseball parks, dancing pavilions, boats and any place where a charge is made to enter and it is desired to have a record of the persons entering and leaving. It can also be used in factories and the like.

In this application the parts are described and shown as applied to a car, though as before stated, the invention is not to be limited to such use.

Another object of the invention is to provide means whereby a printed record is made of the persons boarding and leaving the car in addition to recorders which record the number of persons boarding the car and the number of persons leaving the car.

A further object of the invention is to provide means for indicating on the printed record the stops which the car makes, the parts being so arranged that the number of persons boarding the car and leaving the car will be recorded on the strip between each pair of stop indicating records.

A still further object of the invention is to provide means for feeding the record strip by the operation of the recording mechanism and to provide means for holding the strip against movement when the car is moving.

Another object of the invention is to provide movable steps for actuating the recording mechanisms by the persons boarding or leaving the car.

This invention also consists in certain other features of construction and in the

combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a diagrammatic sectional view through a car showing my invention in use.

Figure 2 is a view of the casing containing the recording means and the means for transmitting the movement of the steps thereto.

Figures 3 and 4 are detail views of the door operated means for indicating the stops.

Figure 5 is an enlarged elevation with parts in section.

Figure 6 is a side view of parts within the casing with the casing in section.

Figure 7 is a section on line 7—7 of Figure 5.

Figure 8 is a similar view but with the parts in a different position.

Figure 9 is an enlarged sectional view of the printing mechanism.

Figure 10 is an enlarged sectional view of the door operated printing mechanism.

Figure 11 is a detail view of the member for transmitting the movement of the printing mechanism to the recording mechanism.

Figure 12 is a fragmentary view of the tape showing the record printed thereon.

As shown in Figure 1 I make the steps 1 of the car vertically movable, the steps being normally held in raised position by the springs 2. Each step carries a rack bar 3 which engages a sprocket 4 on the shaft 5, each shaft having a drum 6 thereon to which is secured a cable 7. These cables pass upwardly over guiding pulleys 8 and the cables which are connected with the bottom steps are connected with the lever 9 and those connected with the upper steps are connected with the lever 10. These two levers are pivoted intermediate their ends and are provided with arc-shaped rack parts 11 which engage sprockets 12. One of these sprockets 12 is located on a shaft 13 and the other one is located on a shaft 14. These shafts 13 and 14 and a third shaft 15 extend

105

110

longitudinally of the car and are rockingly supported. Shaft 15 is adapted to be moved by the movement of the doors 16 of the car. These doors are provided with plates 17 which are adapted to strike the levers 18 which are pivoted intermediate their ends and are connected by links 19 with the lever 20 which is connected intermediate its end to the shaft 15. Thus when the doors are 10 opened the plate 17 will strike lever 18 so as to rock shaft 15 and these parts will remain in this position until the doors are closed again.

Suitably arranged in the car, preferably 15 at one end thereof, is a casing 21 which is provided with a reduced lower part 22. The crank ends of shafts 23, 24 and 25, which are journaled in said casing, project therefrom and these cranked ends are connected 20 with cranks 26 on the longitudinally extending shafts by the links 27 so that the rocking movements of these longitudinally extending shafts will be communicated to the crank shafts.

25 A roll of tape 28 is rotatably mounted between the supports 29 in the casing and this tape is adapted to pass between the supports 30, to a pair of feeding rollers 31 into the extension 22 of the casing. Suitable 30 guiding rollers 32 are provided for the tape. The upper feeding roller 31 has a ratchet wheel 33 connected therewith and a dog 34 for engaging said ratchet wheel is carried by a lever 35 which is pivotally mounted at 35 one end to a support 36 in the casing. A link 37 connects this lever 35 with a bell crank lever 38 which is in turn connected by link 39 with the cranked end of shaft 40 which is connected with crank shaft 23 by 40 the beveled gears 41. Thus the movement of crank shaft 23 will be communicated to the feed rollers so as to cause said rollers to feed the tape from the roller into the extension.

45 A block 42 carrying a printing matrix 43 for printing upon the tape is movably mounted upon a slide 44 which is movable upon the guide rods 45. The slide 44 is mounted to have movement transversely 50 over the tape while the block 42 is adapted to have movement towards and from the tape through the slide, the block being normally held out of engagement with the tape by means of the springs 46 mounted on the 55 guiding studs 47 carried by the slide and engaged by the block. Thus by moving the slide 44 upon the guide rods 45 the character on the block can be printed either at one side or the other of the tape and by pressing upon the block the character can be 60 brought into engagement with the tape.

The means for moving the slide 44 upon the guide rods 45 consists of the link 48 which connects the slide with the cranked 65 end of shaft 40. Thus the movement of

shaft 40 will adjust the slide with the printing matrix and will also feed the tape forward.

The means for pressing the block upon the tape comprises a shaft 49 rockingly mounted in the casing and having a crank part 50 for engaging a groove 51' in the outer face of the block so as to force the block inwardly to press the type against the tape. The shaft 49 is rocked from 75 shaft 24 by means of the link 51 engaging the cranked ends of said shafts 24 and 49.

I provide a pair of registers 53, one for 80 registering the persons leaving the car and the other for registering the persons boarding the car. These registers are actuated by the movement of shaft 49 in the following manner:—A pair of levers 54 are rockingly supported from the supports 30 and the upper ends of these levers are connected 85 by the links 55 with the actuating levers 56 of the registers. The lower ends of the levers are connected by the links 57 with the hooked links 58, the links 57 having eyes which engage eyes on the hooked 90 links 58 and these links 58 are connected together by the cross bar 59, which has eyes 60 at its ends for receiving the links 58. This cross bar 59 is carried by a bar 61 which has its upper end swingingly connected with a yoke 62 connected with the supports 30. I prefer to make the parts 59 and 61 out of wire bent as shown in Figure 11. Yoke 62 lies in the same plane as the 95 connecting eyes of the links 57 with links 58 so that the links 58 can be swung from one side to the other so that their hooked ends 58' will pass under one end or the other of the crank 50 of shaft 49 so that the inward movement of the crank 50 will strike 100 one of these hooked ends and thus move one pair of links 57 and 58 longitudinally to rock the lever 54 to which the pair is connected and thus operate one of the registers 105 53. It will be seen that only that register will be actuated, the hooked link 58 of which is engaged by the crank 50 of the shaft 49, the parts connected with the other register remaining idle. The hooked links 58 are 110 swung from one position to the other by the movement of the slide 44 as the end of the member 61 is connected with the slide, as shown at 63, in Figure 9. The crank shaft 25, actuated by the opening of the door, is connected with a block 64 which 115 carries a printing matrix for printing the word "stop" upon the tape, this block 64 being slidably mounted between the supports 30 and the parts are normally held with the block in its lowest position by 120 means of a spring 65 which is connected with the shaft 25. This block not only acts to print the word "stop" upon the tape, as shown in Figure 12, but clamps the tape against movement as long as the doors are 125

130

closed. As soon as the doors are opened the block is raised off the tape so as to permit the tape to move when a person starts to board or leave the car.

- 5 From the above it will be apparent that when a person starts to enter the car and places his foot on one of the lower steps his weight lowering the step will cause shaft 13 to be rocked and this rocking movement of shaft 13 will rock shaft 40 through the connections shown and this movement of shaft 40 will actuate the feed rollers 31 to cause them to feed the tape from the roll and this movement of shaft 40 will also 10 be transmitted to the slide 44 to adjust the printing block 42 to one side of the tape. When the person places his other foot upon the next step he actuates shaft 14 and the movement of this shaft will cause the shaft 20 49 to rotate so that its crank 50 will strike the block and force the type character thereon against the tape, thus printing a mark on the tape to indicate that a person has entered the car. The movement of slide 25 44 will have swung the member 61 to place the forked ends of one of the links 58 under the crank 50 so that when the said crank is lowered the link 58 will be moved longitudinally to actuate the reigter for indicating 30 that a person has entered the car. Thus a printed record is made of the persons entering the car and the register also registers the number of persons leaving. As soon as the steps are free of the weight of the person 35 the parts will return to normal position by means of the springs connected with the crank shafts.
- If a person should leave the car his weight would first come on the upper step so as to 40 rotate shaft 14. Thus the crank 50 would be pressed against the block before the same had been shifted by its slide so that the mark would be made on the tape at the opposite side from that made by a person entering 45 the car and the second register would be actuated as the second hooked link 58 would be engaged by the crank 50. Then when his weight came on the second step the block would be shifted but no results would come 50 from this as the block would be in raised position and off of the tape. Then when the doors are closed the block 64 would be pressed against the tape to print the word "stop" thereon and to hold the tape against 55 forward movement until the door is again opened. Thus the marks indicating that the persons entering and leaving the car at one stop would appear on the tape between a pair of printed words "stop", so that the 60 persons leaving and entering the car at each stop can be readily seen. For instance, Figure 12 shows that three persons entered the car and four left at the first stop and that four entered and five left at the second 65 stop.

By my invention it will be seen that the car company will have a duplicate record of the persons entering and leaving the car, one record appearing upon the printed strip and the other in the register.

79

It is thought from the foregoing description that the advantages and novel features of my invention will be readily apparent.

I desire it to be understood that I may make changes in the construction and in the 75 combination and arrangement of the several parts, provided that such changes fall within the scope of the appended claims.

What I claim is:—

1. In combination with a vehicle having 80 vertically movable steps, a casing carried by the vehicle, tape supporting means in said casing, tape feeding means, a type carrying block, a slide in which the block is movably mounted, connections for causing the movement of the first step to move the slide and actuate the feeding means, a crank shaft for forcing the block upon the tape, connections from the second step for rocking said shaft when the step is moved, a pair of registers, 85 actuating means for the same including a pair of hooked links, the hooked ends of which are adapted to be engaged by the crank shaft and means connected with the slide for placing the hook of one or the 90 other link under the crank.

2. In combination with a vehicle having 100 vertically movable steps, a casing carried by the vehicle, tape supporting means in said casing, tape feeding means, a type carrying block, a slide in which the block is movably mounted, connections for causing the movement of the first step to move the slide and actuate the feeding means, a crank shaft for forcing the block upon the tape, connections 105 from the second step for rocking said shaft when the step is moved, a pair of registers, actuating means for the same including a pair of hooked links, the hooked ends of which are adapted to be engaged by the crank shaft and means connected with the slide for placing the hook of one or the other link under the crank, a movable block having type characters thereon indicating stop, 110 spring means for holding the said block upon the tape, means for lifting the block off the tape including a rock shaft and means for rocking said shaft by the opening of a door of the vehicle.

3. In combination with a car having 115 vertically movable steps, spring means for normally holding the steps in raised position, a pair of rock shafts in the car, means for connecting the same with the steps, a third rock shaft in the car, means for rocking the same 120 when the car door is opened, a casing, three crank shafts journaled therein and having their cranked ends projecting therefrom, means for connecting said ends with the three shafts, means for supporting a roll of 125 130

tape in said casing, tape feeding means in said casing, means for actuating the same from one of the crank shafts, guide rods located above the path of the tape, slides supported on said rods, a block movably mounted in said guide and carrying a type character, means for moving the slide on the rods by the movement of the crank shaft just mentioned, a crank shaft in the casing having a cranked part for engaging the block to force the same against the tape, means for moving said crank shaft by one of the remaining two of the three crank shafts, a mov-

able block carrying a type for printing the word "stop" upon the tape, spring means for normally holding the same upon the tape, means actuated by the third crank shaft for raising said block, a pair of registers, a forked link connected with each register for actuating the same, and means actuated by the slide for placing one or the other of the hooks of the links under the cranked part.

In testimony whereof I affix my signature.

WILL DEAN BURNON.
